UNITED STATES PATENT OFFICE.

LEVI R. KROUT, OF NORTH WALES, PENNSYLVANIA.

WASHING-MACHINE.

SPECIFICATION forming part of Letters Patent No. 392,348, dated November 6, 1888.

Application filed December 9, 1887. Serial No. 257,379. (No model.)

To all whom it may concern:

Be it known that I, LEVI R. KROUT, a citizen of the United States, residing at North Wales, in the county of Montgomery and State of Pennsylvania, have invented a new and useful Improvement in Washing-Machines, of which the following is a specification.

The invention relates to improvements in washing-machines; and it consists in the construction and novel combination of parts hereinafter described, and pointed out in the appended claim.

In the accompanying drawings, Figure 1 represents a perspective view of a washing-machine embodying my invention. Fig. 2 represents a central vertical section of the same. Fig. 3 represents a plan view of the tub or suds-box with the lid detached. Fig. 4 represents a central vertical section of the dasher-rod and dasher-plate. Fig. 5 represents a face view of the dasher-plate.

Referring to the drawings by letter, A designates a rectangular suds-box, supported on suitable legs and provided with a hinged lid, 25 *a*, which is held closed by spring latches *a'* *a''*, secured to the lid and entering suitable keepers secured to the adjacent edges of the suds-box.

a' is a handle by means of which the lid can 30 be opened when the latches are released from their keepers.

C is a discharge-nozzle secured in an opening on one side of the suds-box adjoining the bottom thereof, and having the arm *c* secured 35 to and standing laterally from its outer end. To the end of said arm is pivoted the end of the corresponding arm of the slide-valve *c'*, the opposite arm, *c''*, thereof extending through the guide-opening made between the curved 40 guide-bar *c'* and the upper and lower projections from the nozzle, to which said bar is secured at its ends. By raising the arm *c''* the slide-valve is moved up from the nozzle to discharge the water from the suds-box.

45 The interior arrangement of the suds-box is as follows:

D are similar vertical partial partitions crossing the corners of the said box at angles of forty-five degrees, so that a horizontal section through the box passing through said partitions will show the contour of an equal-sided

octagon formed by the partitions, as seen in Fig. 3. Each partition D rises a suitable distance above the floor of the suds-box, and has secured to its inner surface, at equal distances 55 from its side edges, the vertical ribs *d*, provided with the longitudinal grooves *d'*.

d' are similar ribs provided with similar grooves, *d''*, and secured to the sides of the suds-box midway between the partial partitions.

The bottom E of the suds-box has secured to it the eight equidistant radial ribs *e*, similar to the ribs *d* *d''*, and provided with the similar grooves *e'*. Four of the said ribs *e* run 65 to the feet of the corresponding ribs, *d*, the alternate ribs *e* running to and under the partial partitions at right angles thereto and midway between the ribs *d* thereon. The said partitions are thus raised above the bottom, 70 so that the water has free access to and presses equally on both sides of them.

F is a circular dasher-plate provided with eight equidistant radial ribs, *f*, provided with the longitudinal grooves *f'*, and similar to the 75 ribs heretofore described.

f'' is a central rectangular opening in the dasher-plate between the inner ends of the ribs *f*, and intended to receive the inner end of the dasher-rod.

G is a cross piece or cleat secured diametrically across the upper surface of the dasher-plate, and having the opening *f''* continued through it.

H is the dasher-rod, squared laterally to enter the rectangular opening *f''*, and provided with a deep longitudinal recess, *h*, to receive the coiled spring *h'*, the lower end of which bears against the pivotal pin *h''*, that has its ends secured in the cross piece or cleat G, and 90 passes through the longitudinal opposite slots *h''* in the dasher-rod. Thus the dasher-plate can be forced upward on the dasher-rod against the spring *h'*, and as the rectangular opening *f''* is longer than the longest diameter of the 95 dasher-rod the dasher-plate is free to oscillate up and down on said rod in the line of the longest diameter thereof.

The dasher-rod passes through a thimble secured centrally to the lid of the suds-box, and 100 has secured upon its upper end, above the lid, the bevel-pinion *i*, meshing with the bevel

gear-wheel I, the shaft of which is journaled in bearings formed in the upstanding brackets J, j, secured at proper points to the lid.

K is a large segmental gear-wheel having its shaft journaled in the brackets J, j', the bracket J being situated centrally between the brackets j, j'. The said segmental gear-wheel has made upon it, centrally between the ends of its toothed portion, the tapering radial socket l for the correspondingly-tapered end of the operating lever-handle L, by means of which the segmental gear is oscillated. The partial partitions, by cutting off the rectangular corners of the suds-box, prevent the vortex formed by the dasher from being interrupted and broken. The coiled spring permits the dasher-plate to rise when the clothes become packed thereunder, and the loose mounting of the dasher-plate on its rod permits it to oscillate and relieve itself when the clothes become packed under one side. The dasher is prevented from rotating by the pivotal pin of the dasher-rod.

M is a frame secured to the upper edge of the suds-box on the side opposite the hinges, and provided with the inwardly and downwardly inclined floor m, the outer wall of said frame being for the attachment of a wringer.

N N are upwardly and outwardly projecting arms secured to the side of the suds-box adjacent to the hinges, and intended to receive and support the lid when raised from the suds-box.

The dasher-rod passes loosely through the opening in the lid, so that it can swing laterally a slight degree in any direction.

The gear-wheel I, meshing with the pinion

i on the opposite side from the segmental gear K, keeps the pinion steady and makes it gear evenly with the segmental gear when the dasher-rod is moved laterally, so that its motion is steadied and equalized. The pinion is loose enough on the dasher-rod to permit this. By equalizing the motion of the pinion the handle can be moved with a regular and even motion, all jerk and jar being prevented.

The gear-wheel I causes the pinion i to remain always horizontal, so that it always meshes at right angles with the segmental gear K, and jar is thus prevented.

Having described my invention, I claim—

In a washing-machine, the combination, with the suds-box, the dasher-rod having a bearing in the lid, and the pinion i on the upper end of the dasher-rod outside of the lid and rotating with said rod, of the segmental gear meshing with said pinion, journaled in the brackets J, j', and provided with the handle L, and the gear-wheel I, journaled in the brackets J, j, meshing with the pinion on the side opposite to the segmental gear, and coacting with said gear to keep the pinion horizontal, and the motion of the dasher-rod consequently equal and regular, if said rod is loose in its bearing in the lid or if the pinion is loose on the dasher-rod, substantially as specified.

In testimony that I claim the foregoing as my own I have hereto affixed my signature in presence of two witnesses.

LEVI R. KROUT.
